ADVERTISING STRAP HANGER

Abel Garcia Sirera, New York, N. Y.

Application May 11, 1937, Serial No. 142,015

6 Claims. (Cl. 105—354)

This invention relates to advertising strap hangers and has for its general object the provision of a strap hanger which carries above the hand grip portion and within the frame, an advertising plate or plates so related to the frame that the latter can be secured to suspending means of varying thickness without impediment on account of the presence of the advertising plates.

Another object of the invention is to provide an advertising strap hanger of the class described in which the space within the frame of the hanger is differentiated into a lower or hand portion and an upper portion bounded at least in part by tongues or grooves in relation to which an advertising plate may be placed by springing, the hanger being provided with means for securing the advertising plate or plates in position.

A further object of the invention is to provide a strap hanger with advertising plates secured at one or both sides above the hand grip portion, the sides of which hanger are of such length and possess such a degree of resiliency that they can be forced slightly together or slightly apart to receive suspending means of different thickness, including an advertising plate or plates of such size and so secured with respect to the frame as to permit the sides of the frame to be warped independently of the plate or plates so that the latter oppose no impediment to the movement of the frame.

Still another object of the invention is the provision of means extending inwardly from the frame at opposite sides, forming either in whole or in part a bridge piece segregating the hand grip portion from the advertising plate holding portion and supporting the advertising plate.

Other objects of the invention will appear as the following description of a preferred and practical embodiment thereof proceeds.

In the drawings which accompany and form a part of the following specification and throughout the several figures of which the same characters of reference have been employed to designate identical parts:

Figure 1 is a front elevation of an advertising strap hanger embodying the features of the invention;

Figure 2 is a similar view with the advertising plate removed, and partly in section;

Figure 3 is a transverse section taken along the line 3—3 of Figure 1;

Figure 4 is a transverse section taken along the line 4—4 of Figure 1;

Figure 5 is a section taken along the line 5—5 of Figure 1;

Figure 6 is a front elevation showing a modified form of the invention;

Figure 7 is a front elevation partly in section of the same form shown in Figure 6 with the plate removed;

Figure 8 is a vertical cross section taken along the line 8—8 of Figure 6;

Figure 9 is a transverse section taken along the line 9—9 of Figure 6; and

Figure 10 is a fragmentary view showing a modified form of the invention.

Referring now in detail to the several figures and first advertizing to that form of the invention shown in Figures 1 to 5, inclusive, the numeral 1 represents a frame which is bent around in 15 the form of a loop to constitute the strap hanger. This frame member may be of any shaped section such as round or square, and is of substantially rigid, although inherently slightly resilient material. The sides 2 and 3 of the frame are pro- 20 longed into lugs 4 and 5 which do not come quite together, but are slightly spaced apart so as to permit the insertion of the suspending means 6 which in the illustration comprise a leather strap. Since it is the intention of the invention 25 to make a strap hanger which may be universally applied to suspending means of different thickness, the space 7 between the lugs 4 and 5 is not of fixed width, but it may be enlarged or contracted by warping the sides of the frame inwardly or 30 outwardly through their inherent resiliency so as to make the strap hanger fit suspending means of different thickness.

Since the primary purpose of the invention is to make a strap hanger which will carry advertising matter, the space within the frame 1 is differentiated into a lower part 8 through which the fingers are inserted when the hand grips the bight of the frame 1 and an upper part which is designed to be occupied by the plates 9 and 10, 40 one on each side. The frame 1 is preferably provided with the inwardly extending bridge pieces 11 and 12 which separate at least in part, the hand space 8 from the sign space above. The sides 2 and 3 and the bridge pieces 11 and 12 are 45 provided with means for retaining the plates 9 and 10. Figures 1 and 3 show that the side pieces have ribs 13 and 14 flanked by grooves 15 and 16 into which the plates 9 and 10 are sprung, said plates resting against opposite sides of the ribs 50 13 and 14. The bridge pieces 11 and 12 are provided with a central channel 17 in which the lower edges of the plates 9 and 10 rest. If the plates 9 and 10 were immovably fixed with respect to the sides 2 and 3 of the frame 1 the capacity of said 55

sides to be warped for varying the space between the lugs 4 and 5 would be inhibited and consequently the invention includes means for providing freedom of motion between the sides 2 and 3 and the plates 9 and 10. Said means consists of lugs 18 and 19 extending inwardly from the opposite sides 2 and 3 and having slots 20 and 21 elongated in the direction in which the sides 2 and 3 move when warped. The opposite plates 9 and 10 are secured together by screw and nut connections 22 and 23, passing through the slots 20 and 21, the elongation of which permits warping of the sides 2 and 3 without impediment from the plates 9 and 10. Said plates must be of such size as to provide a little clearance progressively increasing toward the top of the strap hanger in order to permit relative freedom of movement between the parts.

The fact that the bridge pieces 11 and 12 are discontinuous in the middle, places the fulcrum about which the sides 2 and 3 of the frame oscillate when warped at the point 24 giving the advantage of maximum resiliency.

A slight variant of the invention is shown in Figure 10 in which slotted lugs 25 and 26 corresponding in all respects to the lugs 18 and 19 of Figure 2, are placed inlapping relation adjacent the space 1, the slots in said lugs intersecting so that they may be secured by a single screw and bolt connection instead of the plural bolt and nut connections required in connection with the first described form of the invention. Inasmuch as the bridge pieces 11 and 12 are discontinuous, it is preferred to turn the bottom edges of the plates 9 and 10 as indicated at 27 and 28 in Figure 5, to avoid the danger of cutting the hand against the otherwise sharp edges of said plates.

Figures 6 to 9, inclusive, show a modified form of the invention in which the strap hanger is not clamped to a suspending means, but secured by a swivel connection 29 so that it can rotate axially against the suspending means 30. Otherwise the structural features of this form of the invention are common with the forms already described. The frame 31 is here shown as being formed into an endless circle having a continuous bridge piece 32 segregating the hand grip space 33 from the sign space. Those parts of the frame 31 and bridge piece 32 which bound the sign space, are provided with ribs 34 and grooves 35 and 36 and the channel 37 similar to the corresponding parts as shown in Figures 1 to 5, inclusive.

The sign plates 38 and 39 are sprung into place and secured by means of screw bolt connections 40 and 41 passing through slots 42 and 43 formed in lugs 44 and 45 which extend inwardly from opposite sides of the frame 31. Since the frame 31 is not open at the top, the slots 42 and 43 do not have the same function in this form of the invention as they do in connection with that form of the invention described in Figures 1 to 5, inclusive, but they have another advantage inasmuch as the screw holes in the plates 38 and 39 will remain in alignment with the slots 42 and 43 regardless of the slight shifting in the alignment of the screw holes which will occur from the deforming of the plates 38 and 39 occasioned by springing them into the grooves 35 and 36 and the channel 37.

It will be understood from the above that the invention provides advertising space for the strap hangers of street cars, buses and other public conveyances, that the advertising plates are removable so that the advertisement may be

changed from time to time by the substitution of other plates and that according to the invention it is not necessary to make many sizes of strap hanger to fit suspending means of different thickness which are encountered in various conveyances, but that through the principle of the warping of the sides of the strap hanger independently of the advertising plates, a single type or size of strap hanger is adaptable to all sizes of suspending means.

While I have in the above description disclosed what I believe to be preferred and practical embodiments of my invention, it will be understood by those skilled in the art that the details of construction as illustrated and described are merely by way of construction and not to be construed as restricting the scope of the invention as defined in the appended claims.

What I claim is:

1. Advertising strap hanger comprising a frame formed as a loop having its free ends confronting, in slightly spaced relation, to receive the suspending element to which it is adapted to be secured, the sides of said frame having sufficient resiliency to permit said free ends to be slightly warped to spread or contract the space between said ends to fit suspending means of different thickness, the lower part of the space within said frame providing room for the hand when gripping said frame, a plate for advertising matter fitting the upper part of said frame with some small clearance toward the top, said frame being formed with slotted lugs extending into said space with the slots elongated in the general direction of the movement of the sides of said frame when warped, and fastening means passing through said plate and lugs permitting freedom of movement between said plate and the sides of said frame, so that the frame can be clamped together upon the suspending means without impediment from said plate.

2. Advertising strap hanger comprising a frame formed as a loop having its free ends confronting, in slightly spaced relation, to receive the suspending element to which it is adapted to be secured, the sides of said frame having sufficient resiliency to permit said free ends to be slightly warped to spread or contract the space between said ends to fit suspending means of different thickness, the lower part of the space within said frame providing room for the hand when gripping said frame, a plate for advertising matter fitting the upper part of said frame with some small clearance toward the top, said frame being formed with intersecting lugs with intersecting slots extending from the opposite sides of said frame into said space with the slots elongated in the general direction of the movement of the sides of said frame when warped, and single fastening means passing through said plate and lug permitting freedom of movement between said plate and the sides of said frame, so that the frame can be clamped together upon the suspending means without impediment from said plate.

3. Advertising strap hanger comprising a frame formed as a loop having its free ends confronting, in slightly spaced relation, to receive the suspending element to which it is adapted to be secured, the sides of said frame having sufficient resiliency to permit said free ends to be slightly warped to spread or contract the space between said ends to fit suspending means of different thickness, a bridge piece differentiating the space within said frame into a

- lower part providing room for the hand when gripping said frame, and an upper part, the portions of said frame and bridge piece which bound said upper part being provided with rib structure, plates for advertising matter fitting the upper part of said space and against said rib structure with some small clearance toward the top, said frame being formed with slotted lugs extending into said space with the slots elongated in the general direction of the movement of the sides of said frame when warped, and fastening means passing through said plates and lugs permitting freedom of movement between said plates and the sides of said frame.
5. Advertising strap hanger as claimed in claim 5
10 5, the bridge piece being discontinuous whereby the fulcrum of movement of the sides of said frame is in the lowermost part of said hanger giving maximum resiliency to the sides of said frame.
- 15 10. Advertising strap hanger comprising a frame formed as a loop, a bridge piece extending from opposite sides of said frame differentiating the space within said frame into a lower 15
20 part providing room for the hand when gripping said frame, and an upper part, the portions of said frame and said bridge piece which bound the upper part of said space being provided with rib structure and associated grooves, plates 25 sprung into said grooves from opposite sides and resting against said rib structure, said frame being formed with slotted lugs extending into the upper part of said space between said plates and fastening means passing through said plates 30 and lugs.
- 25 30
5. Advertising strap hanger comprising a frame formed as a loop having its free ends confronting, in slightly spaced relation, to receive the suspending element to which it is adapted to be secured, the sides of said frame having sufficient resiliency to permit said free ends to be slightly warped to spread or contract the space between said ends to fit suspending means of different thickness, a bridge piece extending from opposite sides of said frame differentiating the space within said frame into a lower part providing room for the hand when gripping said

frame, and an upper part, the portions of the frame and bridge piece which bound said upper part being provided with rib structure and associated grooves, plates for advertising matter sprung into said grooves and contacting said rib structure, said plates having some small clearance toward the top with respect to said frame, said frame being formed with slotted lugs extending into said space with the slots elongated in the general direction of the movement of the sides of said frame when warped, and fastening means passing through said plates and lugs permitting freedom of movement between said plates and the sides of said frame so that the frame can be clamped together upon the suspending 15 means without impediment from said plates.

6. Advertising strap hanger comprising a frame formed as a loop, a bridge piece extending from opposite sides of said frame differentiating the space within said frame into a lower 20
25 part providing room for the hand when gripping said frame, and an upper part, the portions of said frame and said bridge piece which bound the upper part of said space being provided with rib structure and associated grooves, plates 25 sprung into said grooves from opposite sides and resting against said rib structure, said frame being formed with slotted lugs extending into the upper part of said space between said plates and fastening means passing through said plates 30 and lugs.

ABEL GARCIA SIRERA.
